PROTECTIVE DEVICE FOR ELECTRIC CIRCUITS

Alfred M. Schmidt, Annaberg in Erzgebirge, Germany, assignor to General Electric Company, a corporation of New York

Application February 24, 1938, Serial No. 192,382
In Germany February 27, 1937

2 Claims. (Cl. 200—123)

The present invention relates to protective devices for electric circuits, more particularly fuse devices, and has for one of its objects the provision of an improved fuse device having means whereby control of the operation of the fuse device may be effected from a point remote from the device either by manual switching or in dependency upon an electric condition at such remote point.

Another object of the invention is the provision of an improved construction and arrangement of parts in an enclosed or cartridge fuse of the type embodying one or more fusible conductors embedded in an arc-quenching filler such as a relatively finely divided refractory insulating material, as for example, quartz sand.

Other objects and the details of that which I believe to be novel and my invention will become apparent from the following description and the claims appended thereto taken in conjunction with the accompanying drawing in which Fig. 1 shows a longitudinal section of an exemplary form of fuse device embodying my invention; Fig. 2 is a plan view of the device of Fig. 1; and Fig. 3 illustrates a modification thereof.

Referring to the drawing, 10 designates an open-ended tubular casing of insulating material, the opposite ends of which casing are closed by contact or terminal plates 11 and 12 respectively. These plates have portions bent over so as to extend respectively along two opposite sides of the casing, and the bent over portions of the plates are formed with contact lugs 11' and 12' projecting outwardly from the casing substantially in a common plane passing through the longitudinal axis of the casing. The advantage of a contact lug arrangement such as just described, is that it may be employed in the mounting of fuse devices of different lengths between stationary supporting contacts having a certain fixed spacing. A further advantage of the described lug arrangement is that it leaves the ends of the casing free for application thereto of other means, such as the remote control means hereinafter described.

Terminal plates 11 and 12 are adapted to have connected therebetween one or more fusible conductors, two of such conductors, designated 13, being employed in the embodiment of Fig. 1, 0 and one of such conductors being employed in the embodiment of Fig. 3. One end of each of the conductors is secured to terminal plate 12 in any suitable manner, as for example, by soldering. The other ends of the conductors of Fig. 1 are secured respectively in openings 14, pro-

vided in terminal plate 11, by means of small bodies of relatively low melting point solder, as indicated at 15. Conductors 13 are embedded in a body 16 of relatively finely divided, refractory insulating and arc-quenching material, such as 5 quartz sand, which fills casing 10.

On the outside of plate 11 is secured a casing 17 which carries two connection terminals 18 respectively on opposite sides thereof. These terminals serve to support a heater element 19 in the form of a coiled wire filament. Within casing 17 and surrounding the heater filament is disposed a body 20 of material capable of being ignited by the filament when the latter is raised to a predetermined temperature. The heater 15 element may, if desired, be provided with a primer of fulminating material, such for example as a mixture of equal proportions of red phosphorus and nitre, to facilitate the ignition of the material of body 20. Body 20 may be comprised of 20 any suitable material readily ignitable and capable upon ignition thereof of producing sufficient heat to melt the securing bodies 15 of solder or fusible alloy. A suitable material for the purpose is aluminium powder with iron oxide (Thermite) and a retarding agent such as, for instance, quartz sand.

In the modification of Fig. 3, the terminal plate 21, corresponding to the terminal plate 11 of Fig. 1, has an outwardly projecting hollow 30 cylindrical boss 22 within which is secured, by means of a body 15 of fusible solder, one end of the single fusible conductor 13. Surrounding boss 22 is a heater coil 23 which has connection leads 24 extending outwardly through an opening 25 in casing 26 to terminals 27, one of which is shown in the drawing, on the side of casing 10.

The connection terminals 18 of the heating device of Fig. 1 and the terminals 27 of the heating device of Fig. 3 are adapted to be connected with an auxiliary circuit. Such an auxiliary circuit may be arranged for energization in accordance with an electric condition at a remote point in the main circuit in which fusible conductors 13 are connected, or may be arranged for energization from a remote source by manual closing of a switch (not shown). When the heater coil 19 of the embodiment of Fig. 1 is raised to a sufficient temperature by flow of current therethrough, the body 20 of ignitable material is ignited, whereupon sufficient heat is developed to melt the bodies 15. In the embodiment of Fig. 3 the heat developed by heater coil 23 is effective, without interposition of ignitable 55

material, to cause melting of the securing body 15. Upon melting of the solder at the securing points of the fusible conductors, the connection between the fusible conductors and the terminal plate 11 of Fig. 1, or the terminal plate 21 of Fig. 3, is interrupted, in that a portion of the fusible conductors melts and the solder tends to flow away, while the sand or other finely divided refractory filling material, forming an insulating 5 incrustation at the openings, inserts itself between the fusible conductors and the terminal plate.

In order to be able to ascertain at some distance whether fuse operation has taken place, 10 there may be provided an indicating device such as shown in Fig. 1. This indicating device comprises a leaf spring 30 one end of which is riveted or otherwise fixedly secured to casing 17, as shown at 31, and the other end of which is 15 releasably secured to casing 17 by means of fusible solder, as shown at 32. This leaf spring is bowed so that upon melting of the solder 32, due to heating of the casing 17 by ignition of the material of body 20, the end of the leaf spring springs 20 outwardly to the position indicated in broken lines in Fig. 1, thus giving indication that sufficient heat has been produced within casing 17 25 to cause melting of the securing bodies 15 and disconnection of fusible conductors 13 from terminal plate 11.

It is contemplated that, in the practice of the present invention, various modifications in the particular details of construction of the exem- 30

plary embodiments illustrated will suggest themselves to those skilled in the art, since, as is believed evident from the foregoing description, the invention is not limited strictly to such details, hence, such modifications as do not depart from the true spirit and scope of the present invention, are intended to be covered by the appended claims.

I claim:

1. A fuse device including in combination, a 10 casing having spaced terminal members, a fusible conductor electrically connected between said members and having one end mechanically joined to one of said members by means of a body of fusible material, a body of sandy arc-quenching 15 material surrounding said conductor adjacent said junction, a body of ignitable material in heat exchange relation to said one terminal member, and an electrically energizable heater element operable for effecting ignition of said ignitable 20 material.

2. A fuse device including in combination, spaced terminal members, a fusible conductor electrically connected between said members and mechanically joined at one end to one of said 25 members by means of a body of fusible material, a body of ignitable material in heat exchange relation to said body of fusible material, and an electrically energizable heater element operable for effecting ignition of said ignitable material, 30 thereby to effect fusion and rupture of said junction.

ALFRED M. SCHMIDT.
